UNITED STATES PATENT OFFICE.

MERRIMAN C. GILLET, OF PHILADELPHIA, PENNSYLVANIA, ASSIGNOR TO STANDARD HEATER COMPANY, OF WILLIAMSPORT, PENNSYLVANIA, A CORPORATION OF PENNSYLVANIA.

STEAM GENERATOR.

Application filed January 18, 1924, Serial No. 687,149. Renewed May 18, 1928.

This invention relates to water heaters of the sectional magazine feed type adapted to generate steam, and has for its object to provide a heater of this character which will be simple in construction, comparatively inexpensive to manufacture, and more efficient in use than those heretofore proposed.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

Figure 1 is a rear elevational view of a heater made in accordance with this invention;

Figure 2 is a transverse sectional view of one of the choke members taken on the line 2—2 of Figure 5;

Figure 3 is a side elevational view of the parts shown in Figure 1;

Figure 4 is a longitudinal sectional detail view of one of the choke members;

Figure 5 is a vertical sectional view taken on the line 5—5 of Figure 1, looking in the direction of the arrows;

Figure 6 is a vertical sectional view taken on the line 6—6 of Figure 7, looking in the direction of the arrows and showing a slightly modified form of the invention; and

Figure 7 is a transverse sectional view taken on the line 7—7 of Figure 6, looking in the direction of the arrows.

1 indicates any suitable supporting members for the boiler, 2 the intermediate individual sectional heating members while 3 indicates the front, and 4 the rear heating members, each of which is provided with the flue spaces 5 and the hollow leg portions 6. The bottom header 7 connects said leg portions 6 of the rear section, by means of the pipes 8. 9 represents water supply pipes to the back heater section 4, which is made larger than are the sections 2, and 10 represents a magazine for fuel which is located between the sections as best illustrated in Figure 7. Said magazine 10 is provided with converging portions 11 to aid in holding the fuel therein and at the lower edges of

said converging portions 11 are disposed a pair of choke members 12 and 13, as illustrated.

14 and 15 represent inclined grate sections provided with a hollow center supporting member 16 as shown. 17 represents any suitable grate shaking mechanism, and 18 the combustion chamber. 19, 20, 21 and 22 represent raised knife edge baffles with which the sections are provided to convey away the gases of combustion to the exits 23, which are joined to the smoke stack or chimney connections 24. Each section 2 between the flue spaces 5 is provided with a plurality of water passages, the outside walls of which are indicated at 25, Figure 7, and underneath the lower ends of said flue spaces 5, each of said sections are further provided with a water passage, the outside wall of which is indicated at 26. In addition to the passages 25 and 26, the leg portions 6 are hollow and form passages connected with said passages 25 and 26, all as will be readily understood. Each of the sections are further provided near the bottoms thereof with the nipples 27, which when joined together, as indicated in Figure 3, form a continuous passage 28 for water extending from the front to the back of the heater. There are two of these passages 28 at the bottom of the heater and there are two similar passages at the top of the heater, as illustrated at 30, passing through the nipples 31, Figure 7. 32 illustrates connections for leading off the heated fluid, and 33 any suitable damper regulator.

As is well known, it is very desirable indeed to provide the choke members 12 and 13 with a water cooling means for these parts are subjected to such very high temperatures that in practice they show a rapid deterioration. In this case, there are provided the top connections 35 and 36 leading from the back section 4 to the choke members 13 and 12 respectively, as will be clear from the drawings, and there are also provided the bottom connections 37 and 38 leading from said choke members to the bottom or return header 7.

Each of the choke members 12 and 13 are provided with a partition 39, see Figures 4 and 7, to provide a pair of channels 40 and

41 for the water. It will be clear from the drawings that as they are subjected to a high temperature, water will pass upwardly through the connections 37 and 38 from the 5 return header 7 to the lowest of said channels 40, around said partitions 39, into the upper of said channels 41, and out said connections 35 and 36 to the back section 4, thus keeping said coke members 12 and 13 relatively cool.

It is further desirable to cool the central supporting section 16 of the grate, and to this end there is provided the pipe 42, see Figure 1, which is conveniently led into said 15 member 16, at its rear end, see Figures 1 and 3 of the drawings. From the front end of said member 16 leads the pipe 43 to the front section 3 as illustrated, so that water continuously passes through said member 20 16, as will be readily understood.

In the somewhat modified form of the invention illustrated in Figures 6 and 7, instead of cooling the members 16 with water it is cooled with air. That is, the said member 25 16 is open at its front end 45, Figure 6, and is provided with numerous holes 46 on its under side communicating with the ash chamber. Cold air is sucked in through the end 45, and holes 46, traverses the member 30 16, and passes out of its rear end into the pipe 47 which is provided with the branches 48 and 49, see Figures 6 and 7. These branches 48 and 49 enter the combustion chamber at the points 50 and 51 respectively, as best shown in Figure 7.

The operation of this steam generator will be understood from the foregoing but may be briefly summarized as follows: Water being admitted through the pipes 9 into the 40 rear section 4, at points well up above the bottom of said section, it strikes hot water already there and this does not strike the hottest portions of the heater, and consequently it does not through excessive contractions and expansions strain or wear out the same to the same degree as would be the case if the water were admitted near the bottom of said section 4 or to a hotter portion thereof.

50 Further, the water from said pipes 9 in the rear section being cooler than the water in the other sections, owing to the fact that it has just entered the boiler, said water circulates downwardly through the water legs 55 6 on the outside edges of said section 4, and thence upwardly through the passages 25 and up to the passages 30. From the lowest portions of the legs 6, said water passes into the succeeding sections 2 of the boiler, 60 through the nipples 27 along the passages 28 to the front of the heater, whence owing to the constantly increasing temperature of the water as it reaches the front of the boiler, said water expands and thereby increases in 65 volume, and rises to the top nipples 31. It

passes thence through said nipples along both top edges of the sections back to the rear section or unit 4. This increase in volume is further enhanced by the water vapor generated in the water and to the pressure which 70 is necessarily exerted by said vapor so that the level of said water will be somewhat higher at the front of the boiler than at the rear thereof with the result that the steam space above said level will be filled with 75 vapor or steam which is constantly deprived of water as it reaches the said rear section 4. It thus happens that said steam will escape through the connections 32 carrying less water than would be the case were the steam 80 allowed to escape directly from its source and not subjected to additional heat, which is very desirable indeed in a heater of the character described. The members 55 and 56 are closed outlet connections provided on 85 the header 7, see Figure 1, by which hot water may be drawn from the heater if desired, while the members 58 and 59 are suitable drain connections also provided in the header 7 for emptying the said heater. As 90 it is often desirable to have a small supply of hot water available at all times, even when the fires are banked, and as the choke members 12 and 13 are under such conditions hot enough to supply it, it is found 95 convenient to tap the connections 35 and 36, and supply them with small pipes, as indicated at 60, see Fig. 1, for this purpose, or a supply of this character may be obtained from the drain pipes, not shown.

A little consideration will show that as the choke members 12 and 13 are always very hot relatively to the other portions of the boiler, the water in the top connections will be always quite hot so that by providing the inlet pipes 9 in the back section or unit 4, and connecting said pipes well up above said choke members 12 and 13, the hot water from said connections 35 and 36 immediately comes into contact with the cold water from the pipes 9, and thus again, serves to temper 105 said cold water and to prevent sudden racking strains due to expansions and contractions which would be experienced by the boiler if said pipes 9 were connected at a point near the bottom of section or unit 4, as has been the custom heretofore. As a matter of fact, there is a continuous circulation of water from the pipes 9 down each water leg 6 of section 4, through the connections 8 to the header 7 and up the connections 37 and 38 back to the choke members 13 and 12 respectively. This circulation of water effectually protects said choke members against the deteriorating action of 110 the fire which other choke members have heretofore experienced.

In addition to this the choke members 12 and 13 are continuous from the front section to the rear section as illustrated in the 115 120 125 130

drawings and may be removed one or both at a time without destroying the rest of the boiler.

In other words, this particular boiler is not only made up of separate sections or units but the units themselves are made in halves as illustrated and the choke members are made in separate pieces so that when any particular portion of the boiler becomes worn out or needs replacing, repairs can be effected at a minimum of expense. In addition to the choke members 12 and 13, being water cooled and providing the continuous circulation above mentioned, the middle supporting member 16 of the grate sections 14 and 15 is likewise either cooled with water or air as may be desired. That is to say, in Figures 1 and 5, there is a constant circulation of water from the rear section 4 through the connections 8, header 7, pipe 42, grate supporting section 16 and pipe 43, back to the front section 3 which latter of course is connected with water passages to said section 4. There being a considerable amount of water vapor or steam formed in said member 16 under the conditions stated, it readily escapes up the pipe 43 into the section 3 and joins the steam or vapor which is given off by the other sections or units of the boiler and thus is the circulation promoted.

In the somewhat modified form of the invention shown in Figures 6 and 7, a portion of the air that is sucked in through the front end 45 of the member 16 may be passed through the holes 46 underneath the grate, and another portion may be passed through the pipes 47, 48 and 49 into the fire box. If the valves 65 are closed the air to the combustion chamber will be cut off and all of the air sucked in at the end 45 will be passed into the ash pit and come up through the grate bars and fuel into the said combustion chamber. Of course, when all of the air sucked in passes through the fuel, the fire will burn more rapidly but when a portion of said air is also delivered into the combustion chamber 18, at the points 50 and 51, as indicated, it mingles with the carbon monoxide gas at said points and further aids in the burning of said monoxide gas to the dioxide form.

In other words, a supply of fresh air at the points 50 and 51 in the combustion chamber will cause heat units to be delivered in the boiler and less carbon monoxide, CO, to escape up through the smoke stack. Stated in other words, when the valves 65 are closed the fire can be more rapidly brought to its hottest condition and steam can therefore be more rapidly produced but when said valves 65 are opened a more economic burning of the fuel is had.

In addition to this, it is, of course, a distinct advantage to introduce hot air into the combustion chamber as is the case here over

what would be the effect if cold air were introduced into the said combustion chamber. That is, the hot air more readily combines with the carbon monoxide present and immediately gives up the heat due to the formation of carbon dioxide before said gases have passed very far through the furnace which would not be the case if cold air were introduced at the points 50 and 51.

The introduction of this hot air into the combustion chamber at the points 50 and 51, located immediately adjacent to or near the choke members 12 and 13 of necessity causes a higher temperature to act upon said choke members than would otherwise be the case. But, due to the fact that partitions 39 are located in said choke members and continuous streams of water are circulated therethrough, said choke members are rendered abundantly able to resist this said higher temperature. Therefore, the result of the construction disclosed is to air cool the grate member 16 and prolong its life, as well as to produce a higher temperature in the furnace near the water to be heated and thus increase the efficiency of the boiler while at the same time preventing the deterioration of the choke members 12 and 13 which would result from said higher temperature if the partition 39 and channels 40 and 41 were not provided.

It is obvious that those skilled in the art may vary the details of the construction as well as the arrangement of parts without departing from the spirit of the invention and therefore I do not wish to be limited to the above disclosure except as may be required by the claims.

What I claim is:

1. In a steam generator, the combination of a plurality of water circulating sections including a front and a back section, said sections being so shaped as to form a choke magazine; a pair of hollow choke members each provided with a pair of water channels disposed along the lower edges of said magazine and forming a continuation of the choke sides thereof; a water inlet to the back section above said choke members; a water header joining the side edges of said back section; upper water connections between one of the channels in each of said choke members and said back section; lower water connections between said header and the other of said channels in each of said choke members; a combustion chamber into which said choke members extend; a grate hollow supporting member provided with means for admitting air thereto associated with said combustion chamber; and valved means for cooling and supporting member.

2. In a steam generator, the combination of a plurality of water circulating sections including a front and a back section, said sections being so shaped as to form a choke

magazine; a pair of hollow choke members each provided with a pair of water channels disposed along the lower edges of said magazine and forming a continuation of the 5 choke sides thereof; a water inlet to the back section above said choke members; a water header joining the side edges of said back section; upper water connections between one of the channels in each of said choke 10 members and said back section; lower water connections between said header and the other of said channels in each of said choke members; a combustion chamber into which said water cooled choke members extend; 15 a grate hollow supporting member provided with means for admitting air to its interior associated with said combustion chamber; and valved air conveying means including air conveying connections between said hollow member and the upper portion of said combustion chamber for cooling said supporting member.

3. In a steam generator, the combination of a plurality of water circulating sections 25 including a front and a back section, said sections being so shaped as to form a choke magazine; a pair of hollow choke members, each provided with a pair of openly connected water channels, said members supported by said front and back sections and disposed along the lower edges of said magazine and forming a continuation of the choke sides thereof; a water inlet to the back section above said choke members; a water 30 header joining the side edges of said back section; upper water connections between one of the channels in each of said choke members and said back section; lower water connections between said header and the other of said channels in each of said choke members; a combustion chamber into which said choke members extend; a grate hollow supporting member associated with said combustion chamber and provided with means for admitting air to its interior and delivering a portion thereof underneath 35 said grate; and valved connections between said supporting member and said combustion chamber constituting means for variably raising the temperature in said combustion chamber in accordance with the unconsumed 40 gases therein while cooling said supporting member.

4. In a steam generator, the combination of a plurality of water circulating sections 50 including a front and a back section, said sections being so shaped as to form a choke magazine; a pair of hollow choke members each provided with a pair of water channels disposed along the lower edges of said 55 magazine and forming a continuation of the choke sides thereof; a water inlet to the back section above said choke members; a water header joining the side edges of said back section; upper water connections between one of the channels in each of said 60 choke members and said back section; lower water connections between said header and the other of said channels in each of said choke members; a combustion chamber into which said choke members extend; a grate 65 which said choke members extend; a grate

hollow supporting member associated with said combustion chamber and provided with means for admitting air to its interior and delivering a portion thereof underneath said grate; and connections between said supporting member and said combustion chamber constituting means for raising the temperature in said combustion chamber. 70

5. In a steam generator, the combination of a plurality of water circulating sections 75 including a front and a back section, said sections being so shaped as to form a choke magazine; a pair of hollow choke members each provided with a pair of water channels disposed along the lower edges of said 80 magazine and forming a continuation of the choke sides thereof; a water inlet to the back section above said choke members; a water header joining the side edges of said back section; upper water connections between one of the channels in each of said choke members and said back section; lower water connections between said header and the other of said channels in each of said 85 choke members; a combustion chamber into which said choke members extend; a grate hollow supporting member associated with said combustion chamber and provided with means for admitting air to its interior and delivering a portion thereof underneath 90 said grate; and valved connections between said supporting member and said combustion chamber constituting means for variably raising the temperature in said combustion chamber in accordance with the unconsumed 95 gases therein while cooling said supporting member.

6. In a steam generator, the combination of a plurality of water circulating sections including a front and a back section, said sections being so shaped as to form a choke magazine; a pair of hollow choke members each provided with a pair of water channels disposed along the lower edges of said 100 magazine and forming a continuation of the choke sides thereof; a water inlet to the back section above said choke members; a water header joining the side edges of said back section; upper water connections between one of the channels in each of said choke members and said back section; lower water connections between said header and the other of said channels in each of said choke members; a combustion chamber into which said choke members extend; a grate hollow supporting member associated with said combustion chamber and provided with means for admitting air to its interior and delivering some of the air underneath said 105 grate; and connections between said supporting member and said combustion chamber adjacent said choke members constituting means for raising the temperature in said combustion chamber. 110

7. In a steam generator adapted to burn 115

fuel the combination of a plurality of sections placed side by side and so shaped as to form a choke fuel magazine; water cooled choke members associated with the lower edges of said magazine and forming a continuation of the choke sides thereof; a combustion chamber into which said choke members extend; a grate to support the burning fuel disposed below said chamber; a hollow supporting member for said grate provided with means to admit air thereto; and passages leading from the interior of said supporting member to above and below the burning fuel constituting means for cooling said supporting member.

8. In a water heater the combination of a plurality of sections placed side by side and so shaped as to form a choke fuel magazine; water cooled choke members associated with the lower edges thereof; a combustion chamber into which said choke members extend; an inclined grate disposed below said chamber; a hollow supporting member for said grate provided with means for admitting air to its interior; and pipe connections between said supporting member and said combustion chamber constituting means for air cooling said supporting member as well as means to deliver air into the upper portions of said combustion chamber to raise the temperature therein.

9. In a steam generator adapted to burn fuel the combination of a plurality of sections placed side by side and so shaped as to form a choke fuel magazine; water cooled choke members associated with the lower edges of said magazine and forming a continuation of the choke sides thereof; a combustion chamber into which said choke mem-

bers extend; a grate to support the burning fuel disposed below said chamber; a hollow supporting member for said grate provided with means to admit air to its interior; and passages leading from the interior of said supporting member to above and below the burning fuel constituting means for cooling said supporting member as well as means to deliver air into the upper portions of said combustion chamber to raise the temperature therein.

10. In a steam generator the combination of a plurality of sections placed side by side and so shaped as to form a fuel magazine and a combustion chamber below said magazine; a grate disposed below said chamber; a hollow supporting member for said grate provided with means for admitting cooling air to its interior and delivering a portion of the same underneath said grate; means for delivering another portion of said cooling air into the upper portion of said combustion chamber; and a valve for controlling the flow of said air into said chamber.

11. In a steam generator the combination of a plurality of sections placed side by side and so shaped as to form a fuel magazine and a combustion chamber below said magazine; a grate disposed below said chamber; a hollow supporting member for said grate provided with means for admitting cooling air to its interior and delivering a portion of the same underneath said grate; and means comprising valved pipe connections for delivering another portion of said air to the top portion of said combustion chamber.

In testimony whereof I affix my signature.
MERRIMAN C. GILLETT.
